[57] CLAIM

The ornamental design for a cart, as shown and described.

DESCRIPTION

FIG. 1 is a front and top perspective view of a cart showing my new design;
FIG. 2 is a front elevational view thereof;
FIG. 3 is a rear elevational view thereof;
FIG. 4 is a side elevational view thereof, the opposite side view being a mirror image of that shown; and
FIG. 5 is a top plan view thereof.

FIG. 1

FIG. 2
